MOTOR OPERATED CIRCUIT BREAKER

John W. May, Pittsburgh, Pa., assignor to Westinghouse Electric & Manufacturing Company, East Pittsburgh, Pa., a corporation of Pennsylvania

Application May 1, 1941, Serial No. 391,243

11 Claims.

(Cl. 200—89)

The invention relates to circuit breakers, and more particularly to trip-free air circuit breakers of the type which are operable by an electric motor and which also have provision for manual operation.

The prior art motor operated circuit breakers of which I am aware are more complicated and expensive than is desired. On standard type motor operated circuit breaker disclosed in Patent No. 2,228,466, issued to Leon R. Ludwig and Ture Lindstrom, January 14, 1941, embodies a relatively complicated and expensive clutch arrangement for coupling the circuit breaker mechanism to the motor unit, disengagement of the clutch being required before the circuit breaker can be manually operated. Moreover, the circuit breaker mechanism requires a special resetting operation by the motor before the breaker can be reclosed after a tripping operation.

Another standard type of motor operated circuit breaker disclosed in the copending application of Ture Lindstrom, Serial No. 156,743, filed July 31, 1937, which became Patent No. 2,240,656 on May 6, 1941, embodies a main operating toggle, one end of which is held by a latching means. A translatable closing lever connected to the knee of the toggle is adapted to be moved to close the breaker by a motor driven crank arm. A second similar lever connected to the knee of the toggle is engageable by a second rotatable crank arm which is manually operable by a handle on the side of the breaker for manually closing the breaker.

Although the above described types of circuit breakers operate satisfactorily, they are more complicated and expensive to manufacture than is desired for some applications.

An object of the present invention is the provision of an improved motor-operated trip-free circuit breaker of simple and inexpensive construction.

Another object of the invention is the provision of an improved motor-operated circuit breaker embodying a very simple trip-free circuit breaker mechanism without any latching means and which automatically resets itself after tripping so that the motor unit only functions to close the breaker and is not required to reset the mechanism.

Another object of the invention is the provision of an improved motor operated trip-free circuit breaker having a movable operating member operated by the motor to close the breaker, the same operating member also being operable manually without interference by the motor operating unit and without disengaging any levers or clutches.

Another object of the invention is the provision of a motor-operated trip-free circuit breaker having an operating toggle actuated by an operating lever pivoted on a fixed support and movable to

close the breaker either by a motor-operated crank arm or by manual means, the crank of the motor unit being arranged to stop in a position clear of the operating lever after closing the breaker.

Another object of the invention is the provision of a motor-operated circuit breaker as described in the preceding paragraphs further characterized by the feature that the motor-operated crank arm is arranged to make an angle of substantially 90° with the operating lever at the time the breaker reaches closed position and also cooperates with the action of the operating toggle so as to provide a mechanical advantage which increases during closing of the breaker and becomes a maximum at the time the breaker reaches closed position.

The novel features that are considered characteristic of the invention are set forth in particular in the appended claims. The invention itself both as to construction and operation together with additional objects and advantages thereof will be best understood from the following detailed description of one embodiment of the invention when read in conjunction with the accompanying drawings, in which:

Figure 1 is a fragmentary front elevational view of a motor-operated circuit breaker constructed in accordance with the invention,

Fig. 2 is a fragmentary vertical sectional view of the circuit breaker taken substantially along the line II—II of Fig. 1, the circuit breaker being shown in the closed circuit position,

Fig. 3 is a view similar to Fig. 2 showing the circuit breaker in tripped open position an instant after operation of the trip device and before the mechanism has been automatically reset,

Fig. 4 is a view similar to Fig. 2 but showing the circuit breaker in open position with the motor-operated crank in an instantaneous position where it is just starting to close the circuit breaker,

Fig. 5 is a diagrammatic view illustrating a portion of the motor energizing circuit, and

Fig. 6 is a fragmentary sectional view through the motor housing at the line VI—VI of Fig. 2, to illustrate the centrifugal brake for stopping the motor and crank arm.

Referring to the drawings, the three-pole circuit breaker illustrated comprises a base 7 of insulating material upon which is mounted three stationary contact means 9, three cooperating movable contact means 11, the arc extinguishers 13, a common operating mechanism 15 and a trip device 17.

The three stationary contact means 9 and the three movable contact means 11 cooperate to form the several poles of the breaker and are disposed side by side on the base 7.

60 The stationary contact means 9 for each pole

of the breaker comprises a stationary main contact 19 and a stationary arcing contact 21 which are electrically connected to a corresponding terminal (not shown) mounted at the upper end of the base 7. The movable contact means 11 of each pole of the circuit breaker comprises a main movable contact 23 secured to a pivoted contact arm 25 of conducting material, and a movable arcing contact 27 secured to an upwardly extending offset projection 29 of the contact arm 25. Each contact arm is electrically connected by a laminated flexible shunt conductor 31 to a corresponding one of the terminals 33 mounted at the lower end of the base 7.

The electrical circuit for each of the poles of the circuit breaker is substantially the same. Beginning with the upper terminal (not shown), the current passes successively along the arc extinguishing structure 13, thence through the main stationary contact 19, the cooperating main movable contact 23, the contact arm 25 and through the flexible shunt conductor 31 to the lower terminal 33.

The assemblage of the movable contact means 11 is pivoted to a U-shaped frame 35 of the operating mechanism 15 by means of a pivot pin 37. A tie bar 39 serves to mechanically connect the three movable contact means 11 for movement together about the common pivot 37. As shown in the drawings, each contact arm 25 is pivoted by a pivot pin 41 to a clamp member 43 which engages the steel tie bar 39, the bolts 45 being provided as the fastening means. A square tube 47 of insulating material is positioned between the tie bar 39 and the clamp members 43 to electrically insulate the poles from each other. Springs 49 are provided for biasing each of the contact arms 25 toward the cooperating stationary contact means 9 with a predetermined normal force. Counterclockwise movement of each contact arm 25 relative to its clamp member 43 is limited by the lower end of the contact arm 25 coming into engagement with a portion of the clamp member 43, as shown in Fig. 3, when the circuit breaker opens.

The construction of the movable contact means 11 is such that the movable arcing contact 27 engages the stationary arcing contact 21 before the main contacts separate during the initial portion of the circuit opening operation, and the arcing contacts 27-21 separate after the main contacts as the circuit breaker moves toward open circuit position so arcing takes place only between the arcing contacts. The sequence of operation of the contacts during closing is substantially the reverse of the opening sequence, the arcing contacts 27-21 engaging prior to the engagement of the main contacts as the circuit breaker approaches closed position and remain in engagement until the main contacts become engaged.

The clamp member 43 of the center pole of the circuit breaker has a bifurcated section 51 formed integral therewith and provided with openings for engaging the main pivot pin 37, openings for engaging a pivot pin which connects the section to the operating mechanism 15, and elongated openings 53 for clearing the fixed pivot pin 55 of the U-shaped operating lever 57 which forms a part of the operating mechanism 15. The pivot pins 37 and 55 extend between the side walls of the frame 35 and are supported thereby.

The central clamp member 43 and its integral section 51 form the switch arm for the movable contact assemblage carried thereby. The sides

of the U-shaped operating lever 57 which engage the fixed pivot 55 are disposed inside of the side walls of the mechanism frame 35, and the bifurcated section 51 of the central clamp member is nested between the sides of the U-shaped operating lever 57. Clockwise or opening movement of the switch arm 51 and the movable contact means carried thereby is limited by the engagement of the central clamp member 43 with a pair of inwardly offset projections 59 of the mechanism frame 35. The projections 59 also limit the counterclockwise or closing movement of the operating lever 57. The clockwise movement of the operating lever 57 is limited by a pair of stop lugs 60 extending inwardly from the sides of the frame 35, these lugs determining the open position of the operating lever.

The flexible shunt conductor 31 for the center pole of the circuit breaker passes between the side walls of the frame 35 and is insulated from the frame by a lining 62 of insulating material on the inside of the frame.

The arc extinguishers 13 may be of any suitable type. One satisfactory type of arc extinguisher which may be used is disclosed in Patent No. 1,896,764, issued to M. W. Brainard February 7, 1933, and assigned to the assignee of this invention.

The operating mechanism 15 of the circuit breaker includes the pivoted operating lever 57 and an operating toggle comprising a pair of toggle links 61 and 63 pivoted together by a knee pivot pin 65. The toggle link 61 consists of a double link formed of a single piece of metal and has its upper end pivotally connected to the switch arm 51 by a pivot pin 67. The lower end of the operating toggle, that is the lower end of the toggle link 63 which is also a double link, is pivotally connected to a linkage indicated generally at 69 which will be hereinafter described. The linkage 69 serves to normally hold the lower end of the operating toggle in a fixed operative position, as shown in Figs. 2 and 4, so that the operating toggle is capable of transmitting the closing thrust of the operating lever 57 to the switch arm 51 to close the breaker and also to hold the circuit breaker in closed position after it has been closed.

The switch arm 51 and the three movable contact means 11 carried thereby are biased to open circuit position by means of a circuit opening spring 71, one end of which is anchored to a pin 73 supported by the frame 35. The outer end of the circuit opening spring 71 is connected to the central portion of the pivot pin 67.

The operating toggle 61-63 is adapted to be moved to a slightly overset position, as shown in Fig. 2, by movement of the operating lever upwardly about its pivot 55 to closed position, thereby effecting closing of the circuit breaker contacts. Movement of the operating toggle beyond the overset position shown in Fig. 2 is prevented by stop projections 74 on the link 61 which engage a stop pin 75 carried by the lower toggle link 63. The operating lever 57 is connected to the operating toggle by means of a connecting link 77, one end of which is pivotally connected to the lower end of the operating lever by a pivot pin 79. The other end of the connecting link 77 is provided with a slot 81 which engages the stop pin 75 and provides a slight lost motion connection between the operating lever 57 and the operating toggle. The connecting link 77 and its slot 81 permit the circuit breaker to be tripped free of the operating lever 57 and also

serve to break the operating toggle during a tripping operation.

A coil spring 80 mounted on the fixed pivot 55 is provided for the purpose of restraining the operating lever 57 in closed position to prevent the weight of the lever from bearing on the knee of the operating toggle 61—63. This spring prevents the operating toggle from being falsely collapsed upon the occurrence of shocks or jarring forces applied to the circuit breaker. The spring 80 is relatively weak, however, so that it will not prevent automatic movement of the operating lever 57 to open position when the circuit breaker is tripped.

The linkage 69 which normally holds the lower end of the operating toggle in fixed operative position, includes a link or lever 83 pivoted at its lower end on a fixed pivot pin 85 supported by the frame 35 and having its upper end pivotally connected to the lower end of the toggle link 63 by a pivot pin 87. The linkage 69 also includes a toggle comprising a relatively long U-shaped link 89 pivoted at its inner end on a fixed pivot pin 91 supported by the frame 35, and a short toggle link 93 disposed inside of the link 89 and connected thereto by a pivot pin 95. The other end of the link 93 of the inverted toggle is pivotally connected to the pivot pin 87 which connects the link 83 to the lower end of the operating toggle.

When the breaker is in closed circuit position, the operating toggle 61—63 is in its slightly overset position in which the knee pivot pin 65 is disposed slightly to the right of a center line A joining the shafts 67 and 81. The links 61 and 63 with the stops 74 resting against the pin 75 acts as a single link in this position, which in combination with the link 83 forms a second toggle with its knee at the pivot 87. This second toggle also occupies a slightly overset position in which the knee pivot 87 thereof is to the right of center line B connecting the pin centers 67 and 85.

The inverted toggle 89—93 normally occupies a slightly overset position in which the pivot pin 87 is disposed slightly above a center line C joining the pivots 91 and 95. This position of the holding toggle is determined by an adjusting screw 97 which is mounted on a lateral extension 96 of one of the sides of the frame 35, the outer end of the toggle link 89 bearing against the adjusting screw 97. The opening bias of the circuit breaker produced by the circuit opening spring 71 is transmitted through the operating toggle 61—63 to the pivot pin 87 and urges the link 83 in a clockwise direction about the fixed pivot 85. Movement of the supporting link 83 in a clockwise direction is normally prevented, however, by the holding toggle 89—93 due to its overset position. The major portion of the opening bias of the circuit breaker is carried by the fixed pivot 85 and only a relatively small component thereof is transmitted to the holding toggle 89—93. This provides the advantage that only a relatively small tripping force is required to cause opening of the circuit breaker despite the large opening forces involved. The holding toggle 89—93 is maintained in engagement with the screw 95 by the small component of the opening bias of the circuit breaker, and the pivot 87 of the lower end of the toggle cannot be moved in a clockwise or tripping direction about the pivot 85 until the holding toggle is moved over center by the trip device 17.

A light retrieving spring 100 is provided for the

purpose of automatically resetting the breaker mechanism to operative position following each opening operation of the circuit breaker. One end of the retrieving spring 100 is anchored to a stud 102 carried by the long toggle link 89 adjacent the pivot thereof, and the other end of the spring is connected to the link 83. The spring 100 serves to automatically reset the lower end of the operating toggle and the linkage 69 to normal position following each tripping operation of the circuit breaker. The spring 100 also acts to insure complete collapse of the operating toggle and cause movement of the operating lever 57 to open position during a tripping operation of the circuit breaker.

The trip device 17 comprises a trip plunger 103, and an electromagnet having a core 105, a pivoted armature 107 and an energizing winding 109. The trip plunger 103 is pivotally connected to the armature 107 by a pivot pin 111, and the armature is pivoted to one leg of the core 105 by a pivot pin 113. The trip plunger 103 extends upwardly through a guide opening in the lateral extension 96 of the frame 35 and the plunger 103 is adapted to be moved upwardly to engage and cause collapse of the holding toggle 89—93 when the electromagnet is energized to thereby cause opening of the circuit breaker.

The energizing winding 109 of the electromagnet may be arranged as a shunt trip to be energized either by fault responsive relays in response to an abnormal condition in the circuit controlled by the breaker or by a shunt control circuit from a remote point, in a manner well known in the art. If desired, however, the trip plunger may be operated by any one of a plurality of overload responsive electromagnets energized directly by current flow through the poles of the circuit breaker.

A relatively light spring 115 is mounted on the trip plunger 103 between the mechanism frame 35 and the bracket 117 which connects the trip plunger to the armature lever 107. The spring 115 is of sufficient strength to move the armature 107 to normal unattracted position when the electromagnet is deenergized.

A cross pin 119 is carried by the upper end of the trip plunger above the lateral projection 96 of the frame 35 for the purpose of limiting downward movement of the trip plunger. The trip plunger 103 has a threaded portion which threadedly engages the bracket 117 and provides a means for adjusting the air gap between the armature 107 and core 105. The trip plunger 103 is adjusted to a position such as to provide a sufficient air gap between the armature 107 and the magnet core 105 when the trip plunger touches the holding toggle to insure that the plunger will be moved upwardly a sufficient distance to cause collapse of the holding toggle 89—93 when the armature 107 is moved to fully attracted position.

The operation of the circuit breaker mechanism as thus far described is briefly as follows: Assuming the circuit breaker to be in the closed circuit position shown in Fig. 2, to manually open the circuit breaker the operating lever 57 is moved in a clockwise direction about its pivot 55 to its open position. This movement of the operating lever is transmitted to the operating toggle 61—63 by the connecting link 77 and causes collapse of the operating toggle inwardly toward the base 7. The circuit opening spring 71 quickly moves the switch arm 51 and the movable contact means 11 carried thereby to open

circuit position as soon as the knee pivot 65 of the operating toggle crosses to the left of the center line A. During this manual circuit opening operation, the lower pivot 87 of the operating toggle remains in fixed operative position where it is held by the linkage 69. The linkage 69 is held in its normal position by the spring 100 when the breaker is open. Downward or clockwise movement of the operating lever 57 is limited by the stop 60.

To manually close the circuit breaker, the operating lever 57 is moved in a counter-clockwise or upward direction about its pivot 55 to the closed position shown in Fig. 2. This movement of the operating lever is transmitted to the operating toggle 61-63 by the link 71 and moves the toggle to the overset position causing movement of the switch arm 51 and the three movable contact means 11 to closed position against the force of the circuit opening spring 71. The circuit breaker is retained in closed circuit position by reason of the overset position of the toggle links 61-63 and 83 as long as the pivot 87 is held in fixed operative position by the holding toggle 89-93. The torsion spring 80 maintains the operating lever in closed position against the stops 59 so that the weight of this lever does not bear against the operating toggle.

The circuit breaker is automatically operated to open circuit position upon operation of the trip device 17. When the winding 109 of the electromagnet is energized either in response to pre-determined abnormal conditions by the fault responsive relays or by the shunt control circuit, the armature lever 107 is moved to attracted position and causes upward movement of the trip plunger 103. The trip plunger when moved upwardly engages the outer end of the holding toggle 89-93 and moves this end upwardly until the pivot 95 crosses a line through the centers of the pivots 91 and 87, whereupon the holding toggle no longer restrains the pivot 87 in operative position. The opening force of the circuit opening spring 71 is transmitted through the operating toggle 61-63 to the pivot 87 and moves the pivot 87 and lever 83 in a clockwise direction about the fixed pivot 85 to tripped position as shown in Fig. 3, causing collapse of the holding toggle 89-93. The switch arm 51 and movable contact means 11 carried thereby are moved to open circuit position by the circuit opening spring 71 and the toggle links 61-63 are moved downwardly as the link 83 moves to tripped position. During this circuit opening movement, the pin 75 on the link 63 engages the outer end of the slot 81 of the connecting link 71, and since the operating lever 57 cannot move any further in a counter-clockwise direction, the link 71 acts to cause collapse of the operating toggle 61-63. As soon as the switch arm 51 reaches open circuit position as determined by the stop portion 59 of the frame 35, the retrieving spring 100 automatically resets the link 83 and holding toggle 89-93 to the normal holding position as shown in Fig. 3. The operating lever 57 is also moved downwardly to open position during tripping operation of the breaker. This movement of the operating lever 57 is initiated as soon as the operating toggle 61-63 begins to collapse and is completed by the resetting action of the retrieving spring 100 which aids in completing the collapse of the operating toggle. The torsion spring 80 is of insufficient strength to interfere with this movement of the operating lever to open position. The parts of the circuit breaker now occupy the

open position illustrated in Fig. 4 of the drawings, and the circuit breaker may be reclosed by movement of the operating lever 57 in a counter-clockwise direction to the closed position shown in Fig. 2.

It will be noted that the circuit breaker is trip free of the operating lever 57. In other words, the contacts will be automatically operated to open circuit position upon operation of the trip device 17, irrespective of the position of the operating lever 57, that is, even though the operating lever may be held in closed position. In addition to being trip free, the mechanism possesses the important advantage that it does not embody any latching means, the linkage 69 constituting the sole means for holding the lower end of the operating toggle in a fixed operative position. Another very important advantage of the mechanism is that it automatically resets itself following each tripping operation, and the operating lever 57 is automatically moved to open position so that the mechanism is immediately ready to reclose the breaker without requiring any special resetting movement of the operating lever.

The contact assemblage, the operating mechanism and the shunt trip device of the circuit breaker are of substantially the same construction as disclosed in the aforementioned copending joint application of Ture Lindstrom and myself filed concurrently with this application.

The circuit breaker is adapted to be operated to closed circuit position by a motor operating unit indicated generally at 121. The motor operating unit has a housing 123 provided with an integrally formed mounting plate 125 by which the unit is mounted on the circuit breaker mechanism frame 35. The mounting plate 125 is removably secured to one of the side walls of the U-shaped mechanism frame 35 by means of a plurality of bolts 127 which engage in openings provided in the side wall of the frame to correctly position the motor operating unit 121 relative to the operating lever 57.

An electric driving motor of the universal type indicated by the reference numeral 129 is mounted within the lower portion of the housing 123. The upper portion of the housing 123 is formed to provide a gear casing 131, and an extension of the armature shaft of the motor 129 projects into the gear casing 131. Upon this extension is secured a worm 133 which engages a worm gear 135. The worm gear 135 is secured for rotation with a counter-shaft 137 rotatably mounted in suitable bearings provided in the gear casing. One end of the countershaft 137 extends through a side of the gear casing and has a crank arm 139 rigidly secured thereon. The free end of the crank arm is provided with a crank roller 141 which is disposed to engage an extension 143 secured to the operating lever 57. The crank arm 139 is adapted to engage the extension 143 of the operating lever 57 and move the operating lever from open to closed position when the crank arm is rotated through a cycle by the driving motor 129.

The electric motor is provided with a control circuit for energizing the same to effect a closing operation of the circuit breaker. A portion of the motor energizing circuit 145 is illustrated in Fig. 5 of the drawings. Included in series in the energizing circuit 145 of the motor is a manually operable control switch 147; and an auxiliary switch 149 which is operated by the movable switch arm 51 of the circuit breaker. The auxiliary switch 149 may be of any conventional construction and is arranged to be closed when the circuit breaker

is open and to be opened when the circuit breaker is closed so that when the manual control switch 147 is closed, and the breaker is open the motor will be energized and start rotation of the crank arm 139.

A rotary switch 151, operated by the shaft 137 of the crank arm, is connected in parallel with the auxiliary switch 149 for the purpose of continuing the energization of the motor after the auxiliary switch opens and until the crank arm has closed the breaker and moved out of the way of the operating lever extension 143. Since the crank arm is thus stopped in a position clear of the operating lever it allows the operating lever to be moved to open position upon tripping of the circuit breaker. This arrangement also permits manual operation of the operating lever without interference by the motor operating unit. The rotary switch includes a contact segment 153 secured to an insulating drum 154 on the crank shaft 137, and a pair of spring contact fingers 155 mounted on an insulating support 157 in the gear casing 131.

The spring contact fingers 155 are electrically connected to the terminals of the auxiliary switch 149 so as to connect the rotary switch in parallel thereto. The segment 153 of the rotary switch is positioned relative to the crank shaft 137 so that the rotary switch becomes closed an instant before the auxiliary switch 149 of the circuit breaker opens, and the segment is of sufficient length so that it maintains the rotary switch closed and the motor circuit energized until the crank arm 139 has effected closing of the breaker and has been rotated to the position shown in Fig. 2 of the drawings in which it is out of the way of the extension 143 of the operating lever 57.

A centrifugal brake mechanism 161 is disposed within the lower end of the motor housing 123 and this brake mechanism serves to bring the motor to a stop promptly after the motor circuit is deenergized by the opening of the rotary switch 151. The brake mechanism 161 comprises a brake shoe carrying arm 163 secured on the lower end of the motor shaft, which carries a pair of brake shoes 165 at its opposite ends. The brake shoes 165 are pivotally mounted on the ends of the arm 163 by pivot pins 167 and are arranged to be moved into engagement with an internal braking surface 169 in the motor casing by centrifugal force when the motor rotates.

The operation of the motor operating unit 121 is briefly as follows. When the circuit breaker is in open circuit position and it is desired to close the circuit breaker, the motor energizing circuit 145 is energized by closing the manual control switch 147. Since the auxiliary switch 149 is in closed position when the breaker is open the motor is energized and rotates the crank arm in a clockwise direction as viewed in Fig. 2. During the rotation of the crank arm by the motor, the crank roller 141 engages the extension 143 of the operating lever 57 as shown in Fig. 4, and moves the operating lever upwardly toward closed position. The rotary switch 151 closes before the auxiliary switch 149 opens so that the motor remains energized and rotates the crank arm through a cycle to effect closing of the breaker. The rotary switch 151 opens the motor energizing circuit after the crank arm 139 has moved the operating lever to fully closed position, and the brake mechanism 161 brings the motor and crank arm to a stop in approximately the position shown in Fig. 2 in which the crank arm is in a position clear of the operating lever extension 143.

It will be noted that the crank arm 139 is disposed so that it makes an angle of substantially 90° with a line drawn from the point of contact of the roller 141 with the extension 143 of the operating lever, to the fixed pivot 55 of the operating lever at the time the circuit breaker reaches fully closed position as indicated by the dotted outline of the crank in Fig. 2. This arrangement provides a mechanical advantage which increases as the circuit breaker approaches closed position and becomes a maximum at the closed position of the breaker. The mechanical advantage is further increased by the action of the operating toggle 61-63 which also provides an increasing mechanical advantage as the breaker approaches closed position and becomes a maximum at the closed position of the breaker. Due to the mechanical advantage provided by the operating toggle and the mechanical advantage provided by the arrangement of the crank arm 139 with respect to the operating lever 57, the load imposed upon the driving motor is substantially constant throughout the closing operation, despite the fact that the tension of the circuit opening spring increases during closing of the breaker and has the force of the contact pressure springs 49 added thereto as the breaker approaches closed position.

Since the circuit breaker mechanism automatically resets itself and the operating lever moves to open position upon tripping of the breaker, the motor operating unit is only called upon to close the circuit breaker, and hence does not have to perform any special resetting operation. The crank arm 139 always stops in a position out of the way of the extension 143 of the operating lever 57, thus making it possible to close the circuit breaker manually by the lever 57 without interference by the motor unit and without disengaging any levers or clutch.

While the invention has been disclosed in accordance with the provisions of the patent statutes, it is to be understood that various changes in the structural details and arrangement of parts thereof might be made without departing from some of the essential features of the invention. It is desired, therefore, that the language of the appended claims be given the broadest reasonable interpretation permissible in the light of the prior art.

I claim as my invention:

1. A circuit breaker having relatively movable contacts, operating mechanism therefor comprising spring means for applying a force to open said contacts, an operating lever pivoted on a fixed support for closing said contacts, a rotatable crank arm disconnected from said lever for engaging and moving said lever to close said contacts, means comprising an electric motor for rotating said crank arm through a cycle to close said contacts and stop the crank arm in a position clear of said lever, said operating lever also being manually operable to close said contacts, means for holding said contacts in fully closed position independently of said operating lever against the force of said spring means, means movable from a normal position to a tripped position to cause opening of said contacts irrespective of the position of said operating lever, means for automatically resetting said movable means and said holding means following a tripping operation and a trip device operable to cause movement of said movable means to tripped position.

2. A circuit breaker having relatively movable contacts, operating mechanism therefor compris-

ing spring means for applying a force to open said contacts, an operating lever pivoted on a fixed support and movable about its fixed pivot from an open position to a closed position to close said contacts, a rotatable member disconnected from said lever for engaging and moving said lever to close said contacts, means comprising an electric motor for rotating said rotatable member through a cycle to close said contacts and stop said rotatable member in a position clear of said operating lever, said operating lever also being manually operable to close said contacts, means for restraining said contacts in fully closed position independently of said operating lever against the force of said spring means, said restraining means including a member movable from a normal position to a tripped position to cause opening of said contacts irrespective of the position of said operating lever, said movable member being biased to tripped position at least when said contacts are closed, holding means for normally maintaining said movable member in its normal position, a trip device operable to cause said holding means to permit movement of said movable member to tripped position, and resetting means for automatically resetting said movable member and holding means to normal position following tripping of the circuit breaker, said operating lever being biased to open position when the breaker is open.

3. A circuit breaker having relatively movable contacts, operating mechanism therefor comprising spring means for applying a force to open said contacts, an operating lever having a fixed pivot about which it is movable from an open position to a closed position to effect closing of said contacts, a rotatable crank arm disconnected from the lever for engaging and moving said lever to close said contacts, means comprising an electric motor for rotating said crank arm through a cycle to close said contacts and stop said crank arm in a position clear of said operating lever, said operating lever also being operable manually to close said contacts, means for restraining said contacts in fully closed position independently of said operating lever against the force of said spring means, said restraining means including a member movable from a normal position to a tripped position to cause opening of said contacts irrespective of the position of said operating lever, said movable member being biased to tripped position when the contacts are closed, a linkage pivotally connected to said movable member for normally holding said member in its normal position, said linkage constituting the sole means for preventing movement of said movable member to tripped position, and a trip device operable to cause said linkage to permit movement of said movable member to tripped position, and means for automatically resetting said movable member and said linkage to normal position following tripping of the breaker.

4. A circuit breaker having relatively movable contacts, operating mechanism therefor comprising spring means for applying a force to open said contacts, an operating lever having a fixed pivot about which it is movable from an open position to a closed position to effect closing of said contacts, a rotatable crank arm disconnected from the lever for engaging and moving said lever to close said contacts, means comprising an electric motor for rotating said crank arm through a cycle to close said contacts and stop said crank arm in a position clear of said operating lever,

said operating lever also being operable manually to close said contacts, means for restraining said contacts in fully closed position independently of said operating lever against the force of said spring means, said restraining means including a member movable from a normal position to a tripped position to cause opening of said contacts irrespective of the position of said operating lever, said movable member being biased to tripped position when the contacts are closed, a linkage pivotally connected to said movable member for normally holding said member in its normal position, said linkage constituting the sole means for preventing movement of said movable member to tripped position, a trip device operable to cause said linkage to permit movement of said movable member to tripped position, and means for automatically resetting said movable member and said linkage to normal position following tripping of the breaker, said operating lever being biased to open position when the contacts are open.

5. A circuit breaker having a movable switch member biased to open circuit position, operating mechanism therefor comprising an operating toggle connected to said switch member, means for normally holding one end of the operating toggle in fixed operative position, a pivoted operating lever movable about a fixed pivot from an open position to a closed position for moving the knee of said toggle to an overset position to thereby cause movement of the switch member to closed position, a trip device operable to cause said holding means to permit movement of said end of the toggle to a tripped position to thereby cause movement of the switch member to open circuit position irrespective of the position of said operating lever, said operating lever being biased to open position when said switch member is in open circuit position, a rotatable crank arm for engaging and moving the operating lever to closed position to close the breaker, means including an electric motor operable to rotate said crank arm through a cycle to close the breaker and stop the crank arm in a position clear of the operating lever, said operating lever also being manually operable to close the breaker.

6. A circuit breaker having a movable switch member biased to open circuit position, operating mechanism therefor comprising an operating toggle connected to said switch member, means for normally holding one end of the operating toggle in operative position, a pivoted operating lever movable about a fixed pivot from an open position to a closed position for actuating said toggle to move the switch member to closed position, said toggle and holding means in the closed position of said breaker acting to hold said switch member in closed position independently of said operating lever, a trip device operable to cause said holding means to permit movement of said end of the toggle to a tripped position to thereby cause movement of the switch member to open circuit position irrespective of the position of said operating lever, said operating lever being biased to open position when said switch member is in open circuit position, spring means for automatically resetting said one end of the operating toggle and said holding means to normal operative position following tripping of the breaker, a rotatable crank arm for engaging and moving the operating lever to closed position to close the breaker, means including an electric motor operable to rotate said crank arm through a cycle to close the breaker and stop the crank arm in a position clear of the operating lever, said operat-

ing lever also being manually operable to close the breaker.

7. A circuit breaker having a movable switch member biased to open circuit position, operating mechanism therefor comprising an operating toggle connected to said switch member, a linkage pivotally connected to one end of said toggle and having a normal position in which it holds said end of the toggle in operative position, a pivoted operating lever movable about a fixed pivot from an open position to a closed position for actuating said toggle to move the switch member to closed circuit position, a trip device operable to cause said linkage to permit movement of said end of the toggle to a tripped position and thereby cause movement of the switch member to open circuit position irrespective of the position of said operating lever, said linkage constituting the sole means for preventing movement of said end of the toggle to tripped position, a rotatable crank arm for engaging and moving said operating lever to closed position, and an electric motor means operable to rotate said crank arm through a cycle to close the breaker.

8. A circuit breaker having a movable switch member biased to open circuit position, operating means therefor comprising an operating toggle pivotally connected to the switch member, a linkage pivotally connected to one end of said toggle and having a normal position in which it holds said end of the toggle in operative position, a pivoted operating lever movable about a fixed pivot from an open position to a closed position for actuating the toggle to move the switch member to closed circuit position, said toggle and said linkage in the closed position of the breaker acting to hold said switch member in closed position independently of the operating lever, a trip device operable to cause said linkage to permit movement of said end of the toggle to a tripped position to thereby cause movement of the switch member to open circuit position irrespective of the position of the operating lever, said operating lever being biased to open position when the switch member is in open circuit position, spring means for automatically resetting said one end of the toggle and said linkage to normal position following tripping of the breaker, a rotatable crank arm for engaging and moving said operating lever to closed position, means including an electric motor operable to rotate said crank arm through a cycle to close the breaker and stop said crank arm in a position clear of said operating lever.

9. A circuit breaker having a movable switch member, a spring for biasing said switch member to open circuit position, operating mechanism comprising an operating toggle pivotally connected to said switch member, a toggle linkage pivotally connected to one end of said operating toggle and having normal position in which it holds said end of the operating toggle in a normal fixed position, a pivoted operating lever movable about a fixed pivot from an open position to a closed position for actuating the operating toggle to an overset position to close said switch member, a trip device operable to cause collapse of said holding toggle linkage to permit movement of said one end of the operating toggle to tripped position and thereby cause movement of the switch member to open circuit position irrespective of the position of said operating lever, said operating lever being biased to open position when

the switch member is in open circuit position, spring means for automatically resetting said one end of the operating toggle and said toggle linkage to normal position following tripping of the breaker, said toggle linkage constituting the sole means for preventing tripping movement of said one end of the operating toggle, a rotatable crank arm for engaging and moving the operating lever to closed position, and means including an electric motor operable to rotate said crank arm to close the breaker and stop the crank arm in a position clear of the operating lever, said operating lever also being movable to closed position by manual means to close the breaker.

15 10. A circuit breaker having a movable switch member biased to open circuit position, operating mechanism therefor comprising an operating toggle connected to said switch member, holding means having a normal position in which it holds one end of said operating toggle in a normal fixed position, a pivoted operating lever movable about a fixed pivot from an open position to a closed position for actuating said toggle to a slightly overset position to close the breaker, a trip device operable to cause said holding means to permit movement of said end of the operating toggle to a tripped position to thereby cause movement of the switch member to open circuit position irrespective of the position of the operating lever, said operating lever being biased to open position when the switch member is in open circuit position, spring means for automatically resetting said one end of the operating toggle and said holding means to normal position following tripping of the breaker, a rotatable crank arm for engaging and moving the operating lever to closed position, means including an electric motor operable to rotate said crank arm through a cycle to close the breaker and stop said crank arm in a position clear of said operating lever, said crank arm being at an angle of substantially 90 degrees to a line drawn from the point of contact of the crank arm with the lever to the pivot axis of the lever at the time the switch member reaches closed circuit position.

15 11. A circuit breaker having a base, relatively movable contacts on said base, a U-shaped frame secured to said base with the sides of the frame perpendicular to the base, operating mechanism 50 for said contacts mounted on said frame comprising an operating lever pivoted on a fixed pivot on the frame and movable from an open position to a closed position to effect closing of said contacts, means for holding said contacts in closed position independently of said operating lever, means movable from a normal position to a tripped position to cause opening of said contacts irrespective of the position of said lever, a trip device operable to cause movement of said movable means to tripped position, means for automatically resetting said holding means and said movable means following tripping of the breaker, a motor unit removably secured to a side of said frame comprising a rotatable crank arm for engaging and moving the operating lever to closed position to close the contacts, an electric motor for rotating said crank arm through a cycle to effect closing of said contacts, and means for causing said crank arm to stop in a position clear of said lever after completing a closing operation, said operating lever also being operable manually to close said contacts.

JOHN W. MAY.
